UNITED STATES PATENT OFFICE.

CLARENCE D. PLATT, OF BRIDGEPORT, CONNECTICUT.

DETACHABLE PLUG.

953,709.

Specification of Letters Patent.

Patented Apr. 5, 1910.

Application filed June 26, 1909. Serial No. 504,404.

To all whom it may concern:

Be it known that I, CLARENCE D. PLATT, a citizen of the United States, and a resident of Bridgeport, in the county of Fairfield 5 and State of Connecticut, have invented certain new and useful Improvements in Detachable Plugs, of which the following is a full, clear, and exact description, whereby any one skilled in the art may make and use 10 the same.

The invention relates to detachable plugs. That is, a device which is utilized for connecting a distributing point of an electrical system with any desired translating device 15 wherein the electric current is to be used.

The objects of the invention are to provide a very simple and compact device which may be readily attached to or removed from the receptacle containing the 20 contacts for electrical distribution.

A further object is to provide a plug, in which the body portion, which makes a suitable contact with the terminal wires through well-known devices, may be inserted and left 25 in place, and the cap portion connecting with the distributing wires may be removed or inserted at will and without liability of undue arcing or rupture of the parts.

A still further object is to provide a body 30 portion for insertion within the receptacle in which the contact parts are arranged with isolated chambers completely protected and in the main body portion, with suitable connecting channels for the insertion of the co- 35 operating plug members.

A still further object, is to arrange a body portion having a central stud contact and a threaded sleeve contact arranged for connection with a receptacle wherein the sleeve 40 contact is readily removable and will insure clean contact connection with the contact clips and conductors of the plug.

Referring to the drawings:—Figure 1 is a view in elevation of the device with a portion of the conducting shell broken away to 45 illustrate the position of one of the contact members. Fig. 2 is a central sectional view of the cap member of the plug with its contacts. Fig. 3 is a bottom plan view of the 50 cap shown in Fig. 2. Fig. 4 is a top plan view of the main body portion of the plug. Fig. 5 is a central vertical section through the plug and contact chambers. Fig. 6 is a bottom plan view of the plug illustrated in 55 Fig. 5. Fig. 7 is a general view of the cap and body portion, the latter cut in section

and illustrating the contact members in perspective, removed from the body portion; the parts illustrating the method of assembling and operating the device. 60

In devices of the class hereinafter described, certain features are required, to make the devices safe for operation and the conductance of current in distribution systems. First of all, the parts must be so arranged 65 that they may be securely attached with reference to the line wire circuits of a receptacle. These receptacles may be either of the well known Edison type or Thomson Houston type, but the plug member, in any instance, must make secure contact with the 70 contacts of the receptacles. The removable cap must also be provided with contacts which, coöperating with the contacts of the body portion of the plug, insure proper electrical connection, without liability of undue 75 arcing, short circuits, and the like. The cap member or removable portion of the plug must be so formed as to be readily inserted or removed from the body of the plug, 80 in order to provide for quick adjustability and permit the use of caps and contact members connected with various translating devices. 85

It is one of the principal objects of the present invention, to arrange all of the several conducting parts, of the device, in such manner, that they may be simply formed and assembled and will insure proper action 90 within reasonable limits of safety. 90

In the accompanying drawings, the numeral 1, denotes the main body portion of the plug, which is provided with a central stud contact 2, and a threaded sleeve contact 3, as is clearly illustrated in Fig. 5. The body portion preferably has a knurled head to facilitate screwing the body portion into and out of the receptacle containing the necessary line wire connections to coöperate 95 with the central stud contact and threaded sleeve contact. 100

The main body portion, below the knurled head, is recessed, providing contact chambers 4, 5, and the exterior of the body portion is threaded as at 6, to receive the threads of 105 the threaded sleeve contact 3.

The recess 4, through an opening 7, provides a receptacle for a spring contact member 8, preferably of substantially U-form or with two leaves between which the contact member of the removable cap 1^a, may be frictionally held and locked and with a suit- 110

able base-extension 9, which may be electrically connected with the central stud contact 2. As shown herein, the contact part 10, is formed with beveled edges to fit within 5 in a beveled opening 11, at the end of the body part and is secured in place and electrically connected with the contact clip 8, by a screw stud 12.

The recess 5, of the body part is formed 10 to receive a similar contact clip to coöperate with the second contact member of the removable cap. As shown herein, this contact clip is of substantially U-form with two upwardly extending arms 13, 14, the latter 15 having a sharp bend 15, which provides a shoulder below which the coöperating contact of the cap will automatically lock. It is also provided with a spring contact member 16, of curved form which will fit within 20 the threads of the threaded shell contact 3, and bear firmly against said shell. It has a double function of exerting a spring locking pressure against a shell to prevent accidental movement and at the same time insures 25 a bright, clean contact for its contact clip, as the shell is screwed over it. It will be noted that no screws or other binding means are necessary for holding this spring contact in place and its resiliency and locking 30 features with reference to the coöperating contact member is always insured.

The upper surface of the body part is slightly dished as at 16^a, and contracted 35 openings 17, 18, connect the upper surface of the body part with the chambers 4, and 5, and act as guides for the contact members 19, 20, of the removable cap portion of the plug. The dished portion 16^a, serves as a guide for insuring insertion of the contact 40 members 19, 20, within the openings 17, 18, inasmuch as, said members, may be placed against the cap in almost any position, and by a partial rotation will engage said 45 openings 17, 18. A slight thrust of the cap through said openings will cause the contacts 19, 20, to be pressed between the upwardly extending arms of the contact clip where, through the shoulders 15 and 23, they will be firmly engaged and locked by 50 lugs 21, 22, which are preferably pressed out of the metal of the contact members 19, 20. These locking lugs 21, 22, serve to separate the leaves of the contact members of the plug when inserted and have the added 55 function of preventing accidental movement and separation of the parts. The contact clip 8, which connects with the central stud contact, has a locking shoulder 23, substantially identical in formation with the locking shoulder 15.

The under side of the cap 1^a, has a recess 24, within which are secured conductors 25, 26, provided with wire-attaching means 27, 28, to which the line wires may be connected. 65 The cap is also provided with a central

opening 29, through which the line wire connections may extend. Of course, the conductors 25, 26, have the projecting contact members 19, 20, suitably secured thereto or formed integral therewith, and the conductors are held to the cap by suitable means such as screws 30, 31.

In addition to the frictional means of the spring leaf 16, for preventing relative rotation of the threaded sleeve contact 3, and 75 body portion, grooves or notches 32, 33, may be formed in the body part to be engaged by lugs 34, 35, pressed in from the material of the threaded shell 3.

The device is so formed that the insulated 80 base-piece or body part and cap may be united or separated at will and always provide proper electrical contacts between the contact clips of the body part and the cap. The chambers, for receiving the contact 85 clips, of the body part, are formed in the side of the tubular body and are connected with the dished guide-portion 16, through the contracted openings 17, 18. Obviously, the contact clips may be readily inserted 90 or removed from the body part upon removal of the threaded sleeve contact and the various parts of the device may be readily assembled without the use of special tools. The contracted openings 17, 18, are of just 95 sufficient size to permit passage of the cap contacts 19, 20, and as the chambers 4, and 5, containing the contact clips are isolated from the surface of the plug except through the contracted openings. What little arcing 100 occurs in the chambers is not appreciable to the user and can do no serious damage. Obviously, the device might be changed as to its several details to a considerable extent without departing from the spirit or 105 intent of the invention.

It will be noted that no metallic parts extend through the upper surface of the body part. In fact, there are no metallic elements within reach of the user when the body part 110 is inserted in a receptacle, except the cap contacts 19, 20, which, of course, are electrically inactive until the cap has been forced down upon the base piece or body part 1. Therefore, there is absolutely no 115 liability of improper use of the device, and all danger of shocks to the user is obviated.

What I claim as my invention and desire to secure by Letters Patent is:—

1. A detachable plug comprising a single piece insulating body portion having a thread upon its exterior, recesses extending into the sides of the body portion and forming chambers for contact devices, a contact clip mounted in one of said recesses and connected with a central stud contact passing through the end of the body portion, and a contact clip having a spring contact finger arranged in the other of said recesses and contacting with a threaded shell contact, 125 130

said shell adapted to be screwed over the surface of the body portion.

2. A detachable plug comprising a single piece insulated body portion having recesses therein, contact clips located in said recesses, a central stud contact and a threaded sleeve contact operatively arranged upon the body portion and connecting respectively with contact clips arranged within the recesses 10 of the body portion, said threaded sleeve contact being screwed upon said body portion and acting as a closure for the contact recesses and as a retainer for one of said contact clips, and contracted guide-openings 15 extending through the body portion from the upper side thereof and connecting with the contact recesses.

3. In a detachable plug comprising an insulating body having contact recesses formed 20 in the sides thereof, a threaded sleeve contact encircling said body and the contact recesses, and forming one of the contacts of the plug, and a contact clip arranged in one of the recesses and provided with a contacting part adapted to yieldingly engage and be held in place by the threaded sleeve contact, a central stud contact, and a contact clip arranged in one of the recesses and with an extended portion adapted to engage the 25 central stud contact.

4. A detachable plug comprising a body part of insulating material having contact recesses formed in the sides thereof, contact clips mounted in said recesses, a threaded sleeve contact and a central stud contact 35 connected respectively with said contact clips, said sleeve forming a closure for the contact recesses and screwed over the exterior of the body part and removably locked thereto.

5. A detachable plug comprising a body part of insulating material having contact recesses formed in the sides thereof, a threaded sleeve contact adapted to be screwed over the end of the body part, and a contact clip 45 operatively arranged in the contact recess and with a contact finger engaging the threads of the threaded sleeve.

6. A detachable plug comprising a body portion having contact recesses formed in 50 the sides thereof, a threaded sleeve contact adapted to be screwed over the end of the body part, and a contact clip operatively arranged in the contact recess and with a spring contacting member engaging the 55 threads of the threaded sleeve.
